(57) **CLAIM**

The ornamental design for a display screen as shown and described.

DESCRIPTION

FIG. 1 is a front, right, top perspective view of a display screen showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view; and,

FIG. 9 is an exploded rear perspective view.

The broken lines showing the remainder of the display screen are directed to environment; the broken lines form no part of the claimed design.

1 Claim, 9 Drawing Sheets
